Attorney

UNITED STATES PATENT OFFICE.

DE WITT C. WHATLEY, OF LIHUE, TERRITORY OF HAWAII.

OIL BURNER.

Application filed July 11, 1922. Serial No. 574,147.

To all whom it may concern:

Be it known that I, DE WITT C. WHATLEY, a citizen of the United States, residing at Lihue, county of Kauai, and Territory of Hawaii, have invented certain new and useful Improvements in Oil Burners; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to oil burners of the type usually employed in connection with boilers for heating water or generating steam.

It is the object of this invention to produce an oil burner that does not require the oil supply tank to be placed above the burner, as is the usual case, but which will lift the oil as high as 22 feet, thus permitting the oil supply or storage to be placed 20 in the basement of permanent plant buildings, or in the lower holds of steamships.

Another object of this invention is to produce a burner that will thoroughly atomize the fuel so that the combustion will be complete and instantaneous, and thereby secure a very high thermal efficiency and avoid the production of smoke. A further object of this invention is to produce a very simple burner that can be cheaply and conveniently 25 made, which will not get out of order, and which can also be employed as a burner for blacksmiths' forges and for similar uses.

In order to more clearly describe my invention, I shall have reference to the accompanying drawing, in which—

Fig. 1 shows a longitudinal section of my improved burner;

Fig. 2 shows a modified form of nozzle, adapted more especially for a square fire 45 box; and

Fig. 3 is a plan view of the burner shown in Fig. 1.

The same reference characters will be used to indicate the same parts throughout the 50 several views.

A body member 1, preferably of circular cross section, is provided with end walls 2 and 3 and with transverse walls 4 and 5. Walls 2, 3, 4 and 5 divide the interior of 55 the body member 1 into three compartments

or chambers A, B and C, the purpose and functions of which will hereinafter appear. End wall 2 has an opening 6 of sufficient size to permit the gland 7 to be inserted therethrough. Within the opening 6 there is a plug 8 provided with an opening 9 which is threaded and adapted to cooperate with the threaded portion of the stem 10. The outer end of plug 8 is recessed for the reception of packing material 11, which is held in place and compressed by means of the gland 12. The stem 10 has a hollow projecting portion 13 whose end is enlarged as indicated at 14 and cooperates with the inclined walls 15 in the wall 4 to form a valve, the purpose of which will appear as the description proceeds. Stem 10 is provided with an enlarged cylindrical portion 16 which cooperates with a central opening in the wall 5 to form a sliding and rotating connection, which is sealed by means of the packing 17 held in place by gland 12. The portion of stem 10 within chamber A is provided with a plurality of holes 18 which communicate with the opening 19 in the tubular member 13.

Steam is admitted into chamber A through the opening in pipe 20, and passes from the chamber through openings 18 and into the tubular opening 19 in member 13 and out through the nozzle 21 into the Venturi tube 22. Pipe 23 extends to the oil supply, and when valve member 14 is withdrawn from the cooperating surface 15 so as to leave a space between the two, the interaction of the steam and the Venturi tube will cause a partial vacuum to be formed in chamber B, which will lift the oil from the supply tank into chamber B where it will become heated before it enters the Venturi tube 22. The steam emerging at high velocity from the nozzle 21, atomizes the oil to some extent and forces it through the Venturi tube at a high velocity, in the same manner in which water is raised and forced into a boiler by an injector. End wall 3 has a central opening 24 in which is threaded a pipe 25 whose inside diameter is larger than the outside diameter of the Venturi tube. An annular space 26 is thereby formed between these two tubes (22 and 25). Secured to the outer end of tube 25 is a burner 27, which may be spherical in shape and provided with a slot 28 through which the atomized oil spray

100

issues, or it may be a flattened portion 29 like that shown in Figs. 2 and 3.

In order to more thoroughly atomize the oil, I subject it to a second atomizing action in the following manner. Steam is admitted into chamber C through tube 30 and this steam passes through the annular space 26 and strikes the stream of oil as it emerges from the Venturi tube 22, and by its action causes the oil to be further and more thoroughly atomized. On account of the double atomization, the oil is thoroughly broken up and enters the furnace in a uniformly minutely subdivided condition, which permits the combustion to be rapid and complete whereby a very intense heat is generated and all smoke and soot eliminated.

Pipes 20 and 30 may be provided with suitable valves for the control of the steam supply. These valves have not been shown, as to supply them does not form part of this invention. In the same manner pipe 23 may be provided within the oil supply tank with an ordinary foot valve, which will prevent the pipe from draining when the burner is inoperative.

Instead of steam, air can also be employed for the operation of the burner, but as steam is usually more readily available than compressed air, I prefer to use the steam.

Where the burner is to be used in a circular fire box or furnace, a tip like that indicated by numeral 27 in Fig. 1 may be used, and where a rectangular fire box is used, a tip like that shown in Figs. 2 and 3 may preferably be employed.

The operation of my device is as follows: The burner is attached to the furnace in any approved manner and pipes 20 and 30 are connected to a source of steam or air under pressure. The pipe 23 is connected to the oil supply tank. Steam is admitted through pipes 20 and 30, and hand-wheel 31 is then rotated so as to open the valve between chamber B and the Venturi tube 22. Oil will then be sucked into the chamber B and into tube 22, and subjected to the first atomization. It then passes into tube 25 where the steam from chamber C atomizes the same the second time. The oil then passes through pipe 25 and through

the tip 27 into the furnace, where the combustion takes place.

Having now described my invention, what I claim as new is:

1. An oil burner having a central chamber adapted to receive oil, means connecting said chamber to a source of oil supply, means for producing a partial vacuum in said chamber whereby oil is caused to flow thereinto, a steam chamber at each end of said central chamber, means for conducting steam into said last named chamber, a tubular valve member extending from one steam chamber through the central chamber, and provided with means cooperating with an opening in the wall between the central chamber and the second steam chamber, whereby the opening may be closed or opened; a Venturi tube secured to said wall, a nozzle secured to said tubular valve member and extending into one end of said venturi, a tube surrounding said Venturi tube concentric therewith and spaced therefrom, whereby an annular passage is formed between said tubes, said passage being connected to one of the steam chambers, and means for controlling said tubular valve.

2. A device of the class described, comprising, in combination, a body member having a central chamber adapted to receive oil, an end chamber on each side of said central chamber for the reception of a fluid under pressure, a tubular valve member rotatably mounted in said body member, a portion of said valve member having a slideable and rotatable connection with one wall of the central chamber, a nozzle secured to said valve member and projecting through an opening in the opposite wall of the central chamber, a Venturi tube secured to said last named opening and adapted to receive said nozzle, a tubular member secured to the end of the body member and surrounding the Venturi tube and concentric therewith, the inner diameter of the tubular member being greater than the outside diameter of the Venturi tube whereby an annular space is formed, a burner on the end of said tubular member, and means for operating the valve member.

In testimony whereof I affix my signature.

DE WITT C. WHATLEY.
